(57) **CLAIM**

The ornamental design for a mosaic anti slip mat, as shown and described.

DESCRIPTION

FIG. 1 is a front elevational view of a mosaic anti slip mat showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is another perspective view thereof;

FIG. 9 is an enlarged view of portion 9 shown in FIG. 7; and,

FIG. 10 is an enlarged view of portion 10 shown in FIG. 8.
